PENCIL.

Application filed April 19, 1924. Serial No. 707,667.

This invention relates to mechanical pencils, and especially to improvements on the structure shown in my copending application entitled "Pencil", filed July 21, 1923; 5 Serial No. 654,847.

The object of the present invention is to generally improve and simplify the construction and operation of pencils of the character described; to provide a structure 10 which permits reduction in the overall length of the pencil; a structure which permits a considerable reduction in the number of parts employed; a structure which permits quick and ready assembly of the parts 15 during manufacture thereof, and further, to provide a pencil which is ornamental in appearance and in which the operating mechanism is entirely enclosed and hidden by a pair of exterior barrel sections.

20 One form which my invention may assume is exemplified in the following description and illustrated in the accompanying drawings, in which—

Fig. 1 is an enlarged central vertical longitudinal section of the pencil.

Fig. 2 is a perspective view of the pencil.

Fig. 3 is an enlarged cross-section taken on line 3—3, Fig. 1.

Fig. 4 is a plan elevation of the interior 30 operating mechanism.

Fig. 5 is a view similar to Fig. 4, but taken at right angles thereto, said view being partially in section and the lower end of the mechanism being enclosed by the lower 35 barrel section and the cone-shaped clamping nut.

Fig. 6 is a perspective view of the rack bar and the lead advancing rod.

40 Referring to the drawings in detail, and particularly to Figs. 1, 2 and 4, A indicates, in general, a mechanical type of pencil, which consists of an upper barrel section 2, a cap or closure therefor, as indicated at 3, a lower barrel section 4, and a cone shaped 45 clamping nut on the point of the pencil as indicated at 5. The barrel sections are tubular or hollow and they enclose a lead advancing or projecting mechanism which is perhaps best illustrated in Figs. 1, 4 and 5.

50 This mechanism consists of a tube constructed of metal or any other suitable material as indicated at 6. The upper end of the tube is slotted as indicated at 7 and this slotted section forms a guide and bearing for

a rack bar shown at 8. The tube is otherwise provided with a central passage 9 which serves as a receptacle for a pencil lead indicated at 10. The lower end of the tube is provided with a tapered blade 11 and the tube is also split as indicated at 12 to form 55 a chuck or clamping member whereby the lead 10 may be grasped. The cone shaped nut indicated at 5 is carried by the threaded extension 11 of the tube and turning movement of the nut in one direction or another 60 will either tighten or loosen the chuck to permit projection of the lead from time to time as it is worn and to permit insertion of new leads.

The upper end of the tube 6 serves as a 70 bearing for a propelling nut generally indicated at B. The upper portion of this nut is slightly enlarged and its exterior surface is corrugated as at 13 for purposes hereinafter to be described. The lower end of the nut 75 is slightly smaller in diameter and cylindrical in shape as shown at 14. A shoulder 15 is thus formed between the enlarged and reduced sections of the nut and this shoulder engages an internal shoulder 16 formed in 80 the upper barrel section 2 and as such forms a stop therefor.

The nut is secured against endwise movement on the tube by means of a pair of annular collars 17 and 17^a, the collar 17 being 85 soldered or otherwise secured to the tube 6 while the other collar 17^a may be formed integral with the tube to permanently secure the nut in position. The nut is, however, free to rotate about the tube 6, but a friction fit is maintained between the collars 17 and 17^a and the nut so as to resist free turning 90 movement.

The nut engages the teeth 18 of the rack bar and rotation of the nut in one direction 95 will therefore advance the rack bar and a pusher rod 19, while rotation in the opposite direction will retract the rack bar and the pusher rod.

The tube 6, the rack bar and the pusher 100 rod carried thereby, the nut 13 and the nut 5, form the complete actuating mechanism of the pencil. This mechanism in itself could be employed as a pencil, but it would not be salable as such as it would be neither artistic 105 nor ornamental in appearance and could not be conveniently grasped by the hand as the tube 6 is fairly small in diameter. Means

are therefore employed for enclosing the mechanism so as to give the pencil the desired diameter and to produce the intended ornamental appearance and finish. This means consists of the barrel sections 2 and 4. The mechanism shown in Fig. 4 is first inserted in the upper end of the barrel section 2 and it is pushed downwardly therein until the enlarged section 13 of nut B engages the internal shoulder 16. Considerable pressure is required to force the mechanism downwardly through the tubular barrel as the corrugated portion 13 forms an interlock between the barrel and the nut; this interlock being essential as the barrel 2 will be employed for the purpose of rotating the nut when advancing the lead. When the mechanism has been placed in position in the barrel section 2, it will be noted that the lower end of the tube 6 will project through the lower end of the barrel 2 a considerable distance. The lower barrel section 4 is then applied so as to assume the position shown in Figs. 1 and 5 and it may here be secured either by being tightly pressed down, cemented or otherwise.

A tight joint is maintained between the barrel sections 2 and 4 by forming a recess in the lower barrel section and an inner ³⁰ ³⁵ ⁴⁰ ⁴⁵ ⁵⁰ ⁵⁵ ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ rack bar to advance or retract the same, a feed bar attached to the rack bar and extending into the lead receiving passage, and a pair of collars on the tube, one at each end of the nut and securing the nut against endwise movement on the tube.

4. A pencil of the character described, comprising a tube having a slot formed in one end and a central passage in the other 10 end, said passage being in communication with the slot and said passage forming a receptacle for a pencil lead, a rack bar slidably mounted in the slotted portion of the tube, a short nut turnably mounted on one 15 end of the tube and engaging the rack bar to advance or retract the same, means for securing the nut against endwise movement on the tube, a feed bar carried by the rack bar and extending into the lead receiving 20 passage, a barrel enclosing one end of the tube and secured thereto, and a second barrel enclosing the other end of the tube and the rack bar, said barrel being secured to the nut and being rotatable with the tube and 25 the first named barrel section.

5. A pencil of the character described, comprising a tube having a slot formed in one end and a central passage at the other end and in communication with the slot, said central portion forming a receptacle for 30 a pencil lead, a toothed rack bar slidably mounted in the rack bar, said rack bar being secured against rotary movement in the tube, a short nut journaled on one end of the tube and engageable with the teeth of the rack 35 bar to advance or retract the same, a feed bar attached to the rack bar and extending into the lead receiving passage, a pair of collars secured on the tube, one at each end of the nut and securing the nut against endwise 40 movement on the tube, a barrel member enclosing one end of the tube and secured thereto, a second barrel member enclosing the other end of the tube and the rack bar, said barrel being secured to the nut and being 45 free to rotate with the tube and first named barrel, and a telescoping turnable connection formed between the turnable and stationary barrel sections.
